UNITED STATES PATENT OFFICE.

THOMAS F. VAN KEUREN, OF SAUGERTIES, NEW YORK, ASSIGNOR TO HIMSELF AND HOWARD FINGER, OF SAME PLACE.

GRATE-BAR.

SPECIFICATION forming part of Letters Patent No. 252,299, dated January 10, 1882.

Application filed November 9, 1881. (Model.)

To all whom it may concern:

Be it known that I, THOMAS F. VAN KEUREN, a citizen of the United States, residing at Saugerties, in the county of Ulster and State of New York, have invented certain new and useful Improvements in Grate-Bars, of which the following is a specification, reference being had therein to the accompanying drawings.

This invention relates to ventilating interlocking grate-bars.

Figure 1 is a plan view, partly in section, of a grate composed of these improved interlocking ventilating grate-bars. Fig. 2 is a side view of the socket side of one of these grate-bars.

The grate-bar A is provided on one side with end and intermediate lugs, *a*, which may be square, round, or oval in cross-section, and on the opposite sides with sockets *b*, into which the lugs of the next adjacent grate-bar fit. Shoulders *c* are formed around the lugs *a* and rims *d* around the sockets *b*. The lugs *a* are tapered outward, and the sockets *b* tapered inward, and when the bars are placed together the former fit into the latter, and the shoulders *c* and rims *d* abut against each other. The tapering of the lugs and sockets facilitates the insertion of the bars and admits of the expansion and contraction of the lugs.

The lugs *a* are provided with holes *e*, which form, with the sockets, a continuous ventilating-tube through the grate from side to side.

The sockets *b* are provided with grooves *f*, which permit the passage of air on the outside of the lugs. When the grate bars are placed together, the lugs being shorter than the sockets, there is a space between the ends of the lugs and the ends of the sockets, and the ventilating-grooves *f* communicate with this space, and thence with the central openings through the lugs.

The last two bars B B of the series may be made without the projecting lug, to facilitate the placing of the same in position.

By means of the interlocking lugs and sockets the grate-bars are locked together, so that an even grate-surface is secured, and spaces being left between the upper and lower edges of the grate bars and the meeting shoulders and rims of the lugs and sockets, there are free passages for air from end to end of the grate-bars. These passages, in connection with the transverse passages through and around the lugs, afford ample circulation of air and prevent melting of the grate-bars.

What is claimed as the invention is—

1. A grate-bar constructed with a lug on one side having a ventilating-passage and with a socket on the opposite side adapted to receive a corresponding lug of another grate-bar, the sides of the socket having ventilating-grooves which communicate with the ventilating-passage of the lug, substantially as described.

2. A grate bar provided with tubular ventilating-lugs and with sockets having ventilating-passages, the lugs and sockets being tapered and adapted to interlock respectively with the ventilating lugs and sockets of a corresponding grate-bar, substantially as described.

3. A grate-bar constructed with lugs *a*, having shoulders *c* and ventilating-passages *e*, and with sockets *b*, rims *d*, and ventilating-grooves *f*, substantially as described.

In testimony whereof I affix my signature in presence of two witnesses.

THOMAS F. VAN KEUREN.
